United States Patent Office

Des. 207,141
Patented Mar. 7, 1967

207,141

STEAM BATH CABINET

Dale L. Cosper, 710 N. Brookfield St.,
South Bend, Ind. 46628

Filed Dec. 1, 1965, Ser. No. 16

Term of patent 14 years

(Cl. D83—1)

Fig. 1.

Fig. 2.

Fig. 3

Fig. 4

FIGURE 1 is a view showing in perspective the steam bath cabinet of the invention;

FIGURE 2 is a front elevational view of the steam bath cabinet as shown in FIGURE 1;

FIGURE 3 is a top plan view thereof; and

FIGURE 4 is an elevational view showing the rear of the steam bath cabinet.

I claim:

The ornamental design for a steam bath cabinet, as shown.
